HAIR COVERING CAP WITH SPACER

Helen N. Olsen, 913 Sir Francis Drake Blvd., Kentfield, Calif.

Filed Oct. 8, 1958, Ser. No. 765,970

2 Claims. (Cl. 132—46)

This invention relates to hair covering caps with spacer member therein and more particularly relates to such caps which are useful in manipulations of the hair on the human head for any suitable hair treatment, and especially in bleaching and tinting operations and the so-called "touch-up" process. It may also find advantageous adaptability in hair waving, shampooing and other suitable manipulations of the hair.

To more fully and clearly define the invention, a prefatory statement of purposes and advantages may be set forth as a premise.

It will be recognized that the human hair has growth from the scalp, and that in the operations of bleaching or tinting or dyeing of the hair, the newly grown hair close to the scalp will have its natural color which will not correspond with the color of the bleached or tinted color of the more extended shafts or strands of hair which have been previously tinted or bleached and subsequently grown to greater length. This new growth of hair closely adjacent to the scalp will become apparent at the scalp in a period of ten to fifteen days. Yet, in such cases it is not desirable to again subject the entire body or mass of the hair to a bleaching or tinting solution because hair is limited in its resistance to bleach or tint solutions which by repeated application to the same length of hair shaft or strand may make the strand susceptible to weakening and resultant breakage.

Again, in tinting or dyeing of the hair, a reapplication of a suitable solution to an entire mass of the hair, including the previously treated hair and the newly grown hair, will produce varying shades or tones of color in the respective growths of hair.

To overcome the difficulties it is customary to resort to a treatment which in the hair-dressing art is generally termed a "touch-up" meaning thereby a treatment of the newly grown hair whereby it is bleached or tinted to correspond with the coloring of the more extended growth of the previously bleached or tinted hair. Such touch-up treatment keeps the hair in a uniform condition throughout the length of the hair shaft, maintains desired shades throughout the hair mass and promotes a soft natural condition, free of dry, brittle, broken and overtreated hair which creates an obviously dry and dyed artificial appearance.

Such a touch-up operation is accomplished by dividing the hair into closely-spaced substantially parallel locks which are preferably continuous across the scalp from front to back, providing therebetween at the scalp what are usually termed "parts" to the hair, thus exposing to manipulation or treatment relatively narrow rows of newly-grown hair close to the scalp, or which is sometimes termed "virgin growth" which has not been previously treated to bleach or tint. Such division into parts fluffs the hair loosely and it is desired to maintain it loosely fluffed until the applied tint or bleach is dried.

Having divided the hair into such parts transversely of the scalp, as shown in Fig. 6, a tinting or bleaching solution is applied to the newly grown hair shafts ad-

2

jacent to the scalp made accessible by said parts, such application being conveniently made by means of a suitable small swab, usually a tuft of absorbent cotton mounted at one end of a manually manipulable swabstick. After such application to the newly grown hair, it is customary to dry the applied solution on the hair, which may be accomplished by enclosing the hair and the scalp within a heat-retaining cover and drying it by the confined heat of the body temperature or by mechanical drying apparatus or both. During the drying operation it is desirable for reasons stated above, that the previously tinted or bleached hair shall not be depressed into contact with the newly treated hair, and that the hair mass be maintained loose and readily permeable by the heat.

It is, therefore, an object of the invention to provide a cap or covering for loosely and freely enclosing the hair and which will puff or balloon away from the hair mass, such cap readily and resiliently gripping the head adjacently to the scalp line. A further object is to provide in a balloon-type of hair covering cap a means for supporting the crown portion or peak of the cap away from the hair at the apex of the cap.

One form in which the invention may be exemplified is described in this specification and illustrated in the accompanying drawing in which:

Fig. 1 is a side elevation of a cap of the invention.

Fig. 2 is an exploded side elevational view of the disassembled parts of the cap of the invention.

Fig. 3 is a vertical section transversely from front to rear of the cap as shown in Fig. 1.

Fig. 4 is a top plan view of the cap.

Fig. 5 is an enlarged perspective view of a spacer member shown in Figs. 1, 2 and 3.

Fig. 6 is a front elevational view illustrating a head of hair having parts therein preparatory to operational treatment in use of the cap.

Referring to the drawing in which like reference characters indicate corresponding parts in the several views, 9 indicates generally a head of hair which is the subject of treatment, and 10 indicates generally the cap of the invention, having a balloon-like or bulbous body portion 11 of flexible sheet material which preferably is a moisture-impervious plastic sheet material smooth at both surfaces, since such a material is non-absorbent and adapted for extroversion for readily rinsing and cleaning of the cap. The crown portion 11a of the balloon-like or bulbous body is of much greater transverse diameter than the outer diameter of the hair mass it is intended to enclose, so that when mounted upon the hair it will stand out from the hair without substantial pressure upon the hair body. The cap has an opening 12 normally of less diameter than the crown portion for receiving therethrough the hair and scalp portion of the head, said opening being edged by a continuous elastic crimping or shirr band 13 which is enclosed by the edge portion of the plastic sheet material surrounding the opening 12, the body portion of the sheet material enclosing the elastic band being crimped or shirred by gatherings as at 14, thus contracting the surplus length of material enclosing the elastic band, whereby the opening may normally be of smaller diameter than the crown portion and may be manually spread to a larger diameter to pass over the hair and return to the smaller diameter responsive to the elastic band, thereby gripping the scalp adjacently below the hair line. The elastic band may have a width sufficient to provide a band which lies flatly against the head. The crimped gatherings 14 at the edge of the opening provide plaits 15 in the crown portion adjacent to the band. When the elastic band contracts, the crimped portion against the head, the hair puffs the balloon-like body radially outwardly, and the plaits 15 are bent radially outward at an angle relative to the crimps of the band portion, as indi-

70

cated 15a. Thus the crown portion of the cap adjacent to said opening is puffed radially outwardly from the hair adjacent to the band and the hair line of the scalp, thereby eliminating pressure upon the fluffed hair in the region of the hair line.

At the axially central crown portion of the cap opposite the opening 12, there is mounted an elongated spacer member generally indicated 16 which has one of its ends connected to the sheet material of the cap body, and which extends inwardly from the peak or crown of the cap. This spacer member preferably is tubular and formed of a substantially rigid plastic, having orifices 17 therethrough intermediate its ends. The connection of the spacer member to the sheet material of the flexible cap is preferably a releasable non-perforating attachment, so that it may be removed for any desired purpose, such as cleansing the cap. Such a connection may be accomplished by forming the flexible sheet material of the cap body closely against the connecting end of the spacer member and deforming the flexible sheet material of the cap into close contact with the adjacent circumferential side wall of the spacer member and releasably clamping the sheet material to the end portion of the spacer member by a clamping cup 18 which snugly encloses the sheet material and the end of the spacer member relatively. At its opposite end portion the spacer member is provided with radially spread feet 19, preferably integral with the spacer member, and extending substantially perpendicularly radially outwardly from the axis thereof in the nature of a spider member. The feet are preferably formed by slitting the end portion of the wall of the tubular spacer member for a suitable length axially longitudinally and bending the respective segments radially outwardly preferably at an angle substantially perpendicular to said axis. Thus, while the thin plastic sheet is per se quite light in weight, such weight as there is centrally of the crown, is held away from the fluffed hair by the relatively large area of the feet resting against the hair at the crown of the head.

If desired, any suitable tie means 20 may be employed to more securely position and hold the cap on the hair, manifestly being of length sufficient to extend from relatively opposite positions of the elastic band and for tying under the chin.

In operation the cap is placed upon the head by means of the opening 12 and stretching and then contracting the elastic band 13, the feet 19 resting lightly upon the crown of the hair. The flexible balloon-like portion is thus held substantially spaced relative to the hair at its circumfer-

4
tial portion by the radially outwardly extending plaits, and by the spacer member at its crown cover portion, providing ample space within the cap for the hair to remain fluffed and to provide an area of space in which heat of the body or from a mechanical device may operate to dry the hair.

The manner of operation of the cap in permanent waving of the hair is basically the same as in bleaching and tinting operations as described above, though in permanent waving the entire mass of the hair may be subjected to a softening or so-called waving lotion. When the hair has been divided into locks and wound on curling rods on the head and the waving lotion applied thereto the softening action of the lotion is often accentuated by some form of heat, either from the body or mechanically in which case the cap of the present invention may be employed as a covering for the wound hair to promote the action of the waving lotion, or for drying the hair after the waving lotion has been neutralized as is customary.

Having thus described the invention, what is claimed as new and patentable is:

1. In a cap for covering the hair having a balloon-like body of flexible sheet material provided with a crown portion and an elastically expandable and contractible opening of lesser diameter than the crown portion for receiving therethrough the scalp and hair of the human head, the combination therewith of a tubular spacer member extending into the balloon-like body and having one end connected at the apex of the crown of the cap substantially axially of the said crown portion, the said spacer member having a radially spread foot portion at its opposite free end, the said sheet material of the cap circumferentially enclosing the connected end portion of the spacer member, and a clamping cup releasably engaged around the said connected end of the spacer member and the sheet material therearound, whereby the spacer member may be selectively removed and replaced in the crown of the balloon-like cap body.

2. A cap for covering the hair as set forth in claim 1, the said spacer member having orifices longitudinally thereof.
